UNITED STATES PATENT OFFICE.

BERNARD DONOHUE, OF YONKERS, NEW YORK.

WRENCH.

SPECIFICATION forming part of Letters Patent No. 268,784, dated December 12, 1882.

Application filed April 14, 1882. (No model.)

To all whom it may concern:

Be it known that I, BERNARD DONOHUE, a citizen of the United States, residing at Yonkers, in the county of Westchester and State 5 of New York, have invented new and useful Improvements in Wrenches, of which the following is a specification.

This invention relates to an improvement upon the duplex wrench for which Letters 10 Patent of the United States numbered 238,369 were secured to me March 1, 1881. The device illustrated in said Letters Patent combines in a single tool two sets of gripping-jaws adapted to grip either a surface having parallel faces—such as a square or polygonal headed nut—or an irregular or cylindrical body—such as a pipe or cylinder—the screw-threaded shank or stock in said duplex wrench being provided with two stationary jaws, and a slide 15 operated by a screw-threaded nut being provided upon one side with a rigid jaw and on its opposite side having a yielding spring-jaw adapted to serve, in conjunction with one of the stationary jaws, as a pipe-wrench. The 20 slide in said duplex wrench was provided with a recess for the movable spring-jaw, which was formed with a shank having near its rear end a slot through which the pin passed for the purpose of pivotally connecting the jaw to the 25 slide. The bottom wall of the recess in which this jaw was pivoted was made straight and parallel with the axis of the stock throughout its entire length, and the spring secured upon said level bottom wall, so that the outward 30 swing of the toothed end pressed the spring down upon the wall and constituted the bottom of the said recess.

It is the object of my present invention to provide improved means for arresting the rear 35 or tail end of the jaw as its forward toothed end is swung out, and at the same time to avoid any increase in size of the slide; also, to provide an improved arrangement of spring and means for checking the inward movement 40 of the tail end of the jaw as its forward end is swung outwardly or away from the slide. These objects I attain, first, by forming the 45 slide with a raised seat or solid abutment in the rear end of the recess in which the jaw is pivoted, so that when the forward toothed end

of the jaw is swung outwardly its tail end will be arrested at the proper moment by said raised seat or solid abutment in the recess, and thereby limit the movement of the pivoted jaw; secondly, by locating a spring in a recess 55 that is formed in said raised seat or solid abutment, so that the said spring, while acting to throw the tail of the jaw outwardly, will be compressed within the recess when the forward toothed end is swung out. 60

In the annexed drawings, Figure 1 illustrates the duplex wrench; Fig. 2, a longitudinal section of the same; Fig. 3, a side view of a form of wrench particularly adapted to serve as pipe-tongs; Fig. 4, a longitudinal section 65 of the same, and Fig. 5 a view of the pivoted jaw detached.

The letter A indicates the stock of a wrench, this said stock being provided at one of its ends with a T-head, B, adapted to constitute 70 the fixed or stationary jaws of the wrench, and being provided at its remaining end with the usual handle, C. The movable slide D, which is arranged to slide longitudinally upon the stock, is formed with a rigid jaw, D', this 75 rigid jaw of the slide having a plane gripping-surface for serving, in conjunction with the plane gripping-surface B' on the T-head, to grip nuts or the heads of bolts, as is usual in nut-wrenches. The slide is provided at its 80 rear end with a groove, D², in which sets an angular flange formed in the screw-nut E. This screw-nut travels upon the screw-threaded portions A' of the stock, so as to operate 85 the movable slide and adjust the jaws to and from each other. The slide is formed with a recess, F, between the walls of which is pivoted the jaw G. The forward end of this pivoted jaw, which extends out from the recess of the slide, is provided with an inclined or 90 beveled gripping-surface, G', which is serrated, so as to take better hold upon the object to be grasped, and the fixed jaw B² of the T-head is concaved, with or without serrations, whereby such articles as a pipe or cylinder can be 95 gripped by these jaws in the manner of a pipe-wrench.

In turning or twisting a pipe or cylinder it will be found that the severe strain to which the pivot is subjected will be apt to break the 100

latter, and hence to relieve the pivot from such strain, and to transfer the pressure from the pivot directly to the slide I form the free end or head of the pivoted jaw with shoulders g^2 , 5 which, when the jaw is closed down in the recess, as shown, lie against the ends of the vertical walls that are formed by recessing the slide. Hence when the jaw is turned upon its pivot so as to move its serrated head outwardly 10 from the recess the shoulders g^2 will be brought against said end walls and bind upon the same, thus relieving the pivot-pin from strain. In order to effectively limit the movement of the pivoted jaw, I provide in the rear end of the 15 recess F a raised seat or solid abutment, H, that is formed by a raised portion of the slide at this point. This seat or abutment is located directly under the rear end or tail of the pivoted jaw, and it is provided with a socket, h, 20 in which is fitted a spring-cushion, I, composed either of a metal spring or of an elastic block of rubber or other elastic material. This spring acts against the tail of the pivoted jaw, and causes the same to normally lie in the recess, 25 as shown, the upper side of the body of the jaw being about flush with the top edges of the vertical walls that are at the sides of the recess. Hence when the serrated end of the jaw is raised or moved outwardly this spring constitutes a yielding resistance to the jaw, and in 30 case of great pressure upon the free end of the jaw its tail will compact the spring and be forced against the raised seat H.

In the duplex wrench shown in my said Patent No. 238,369, the spring bears against the jaw substantially under the pivot; but in the present instance the tail is recessed at its under side, as at K, so as to allow space for the spring and the elevated stop or seat, and the 40 spring bears against the end of the tail portion of the jaw some ways back of the pivot, which passes through a perforation in the jaw at a point forward of the elevated seat. It will thus be seen that these parts of the wrench can be 45 arranged in a compact manner, and that the bulk of the wrench will not be increased. The wrench will work smoothly and efficiently, and be found extremely serviceable. The wrench is neatly finished, and the outer edges of the

slide and double stationary jaw are rounded off, 50 so as to give to the same a smooth and finished exterior.

In Figs. 3 and 4 a single instead of a double rigid jaw is provided in conjunction with the pivoted jaw, and in Fig. 4 a coiled spring is 55 shown, while in Fig. 2 an elastic cushion is fitted in the recessed seat.

I am aware of the Letters Patent No. 59,571, issued November 13, 1866, to W. Evans; No. 82,513, issued September 29, 1868, to J. Goodin; 60 No. 172,155, issued January 11, 1876, to O. B. North, and the Letters Patent of Great Britain No. 2,755, A. D. 1853, and the several devices shown in said patents form no part of my invention in the present case. 65

Having thus described my invention, what I claim is—

1. The combination, in a duplex wrench, with the stationary jaw, of the slide adjustably held upon the wrench-stock, said slide having a recess which is provided at its lower or rear end with a raised seat or abutment located between the side walls of said recess, a jaw pivoted within the latter at a point between said seat and the upper end of the recess, and 70 having its tail end projecting over said raised seat or abutment, substantially as described. 75

2. The combination, in a duplex wrench, of the stationary jaw, the slide adjustably held upon the wrench-stock, said slide having a recess provided at its rear end with a raised seat or abutment located between the side walls of 80 said recess, a jaw pivoted within said recess at a point about midway of its length, said jaw being recessed or cut away upon its under edge 85 to form a tapered or thin extremity, which projects over the raised seat, and an elastic cushion received by a socket in the raised seat and bearing against the under surface of the rear end of the pivoted jaw, substantially as described. 90

In testimony whereof I have hereunto set my hand in the presence of two subscribing witnesses.

BERNARD DONOHUE.
